UNITED STATES PATENT OFFICE.

JOHN E. FULLER, OF NEW YORK, N. Y., ASSIGNOR TO CALEB COLES
DUSENBURY, OF LAKE MAHOPAC, NEW YORK.

MAGNETO-CIRCUIT CLOSER.

SPECIFICATION forming part of Letters Patent No. 617,858, dated January 17, 1899.

Application filed November 10, 1898. Serial No. 696,001. (No model.)

To all whom it may concern:

Be it known that I, JOHN E. FULLER, a citizen of the United States, residing at the city of New York, in the county and State of New York, have invented an Improvement in Magneto-Circuit Closers, of which the following is a specification.

In telephone instruments it has heretofore been usual to provide a rotary magneto-generator for ringing the call-bell at the distant station, and in this instance the circuit through the transmitting and receiving instruments has usually been changed by a switch actuated by the weight of the receiving instrument, so that the pulsations from the magneto-generator do not pass through the transmitter or receiver, and in lifting down the receiver the circuit is changed so as not to pass through the magneto-generator.

In the present invention a switch is actuated automatically by the current set up in the generator so as to include in the external circuit the circuit passing through the coils of the armature in order that the external circuit and the distant call may be actuated by the rotation of the armature, and when the rotation ceases the demagnetization of the armature or the field-magnet breaks the circuit through the armature-coil, thereby throwing out the resistance of such armature-coil and establishing the circuit containing other transforming devices, and while the present invention is especially adapted to telephonic instruments it may be used whenever a magneto-call is available and in which it is desirable to throw out of circuit the coil of the armature.

In the drawings, Figure 1 is a plan view, partially in section, illustrating the present improvement. Fig. 2 is an elevation of the switch mechanism with the armature and connecting parts in section near the line 2 2, and Fig. 3 is a diagram of the circuit connections.

The field-magnet is advantageously made of bars A, bent into a U shape and several bars grouped together and bound by the screw-clamps 3, and the pole-pieces B are connected with the field-magnets and are concave on their opposing faces to receive between them the shaft C, armature-base D, and coil E, and the shaft C is advantageously

supported by the end pieces or frames F, and the pinion G is upon one projecting end of the shaft C, and the gear-wheel H is upon a shaft I and rotated by a crank K or other suitable motive power.

By the rotation of the armature a current is to be set up through the helix of the armature, and this current is available in an external circuit for any desired work or transformation, and the switch L is attracted by the magnetism of the armature or pole-pieces to close the circuit or to break the same as the magnetism may be set up or augmented. I have represented this switch L as attached at one end 5, and the free end is near one end of the armature-base, and this switch is either of magnetic material or provided with a plate of magnetic material at the end, so that the augmentation of the magnetism in the armature-base will attract the moving end of the switch and effect the opening or closing of the circuit.

In Fig. 3 I have shown in the circuit a transmitting instrument at M, a receiver at N, a battery at O, and a bell at P, and it will be apparent that when the armature is rotated and the magnetism of the armature-base or core is augmented the circuit will be closed through the armature-coil, and hence the current will be directed through the external circuit for actuating the call-bell at the distant station, and as soon as the rotation of the armature ceases and the core or armature-base demagnetizes, or partially so, the spring of the switch L closes the external circuit through the back-stop G, thereby cutting out the armature-coil and lessening the resistance in the telephonic circuit, and this operation is the same, regardless of the instruments that are included in the working or external circuit, and where the field-magnets are in series with the armature-coil the magnetism of the cores of the field magnet or magnets will be augmented and the switch L may receive its motion from the augmentation of the magnetism in either core.

I have represented the switch as supported by two spring-arms 7, that are fastened at one end rigidly, and the other ends carry the switch L, that is of magnetic material, and one circuit-wire comes to the spring portion of the

switch, and the spring closes the switch against the back-stop 6 when the magnetism is diminished, and when the magnetism is augmented the movement of the switch by the 5 attraction closes the same against the stop 9, which is in the circuit containing the armature-coil. I, however, do not limit myself to the arrangement of the circuits herein represented, because the automatic switch, 10 brought into action one way or the other automatically by the change of magnetism in the adjacent parts, can be availed of in any arrangement of external circuits, the spring moving the switch in the opposite direction 15 to the magnetism.

I claim as my invention—

1. The combination with the field-magnet, the armature and its coil, of a switch having magnetic material that is acted upon by the 20 change of magnetic strength, and circuit-closing stops at opposite sides of the switch with which the switch is brought into contact in one direction by the action of a spring and in the other direction by the action of the 25 magnetism, substantially as set forth.

2. In a dynamo, the combination with the revolving armature having a core and coil, of

a switch carried by such armature and magnetic material upon the switch, by which the switch is moved by the increase of magnetism, circuit connections from the switch whereby the armature-coil is brought into the circuit when the magnetism of the armature is augmented and in which the automatic movement of the switch cuts out the armature-coil when the rotation of the armature ceases, substantially as set forth. 30 35

3. The combination in a telephonic circuit containing a transmitting and receiving instrument and a call-bell, of a dynamo-generator having an armature with a core and coil, a switch upon the armature, a spring for carrying the same, circuit connections that close the external circuit when the dynamo is at rest, and circuit connections that bring in the 40 45 armature-coil automatically by the action of the switch when the armature is revolving, substantially as set forth.

Signed by me this 1st day of November, 1898.

JOHN E. FULLER.
